UNITED STATES PATENT OFFICE.

HARRIS W. SLATER, OF LAKE MAHOPAC, NEW YORK, AND JAMES T. HOGAN, OF JERSEY CITY NEW JERSEY, ASSIGNEES TO THE NATIONAL MACHINE COMPANY, OF MAMARONECK, NEW YORK, A CORPORATION OF NEW YORK.

STOP-MOTION FOR SEWING-MACHINES.

No. 894,073.

Specification of Letters Patent.

Patented July 21, 1908.

Application filed August 23, 1907. Serial No. 389,767.

To all whom it may concern:

Be it known that we, HARRIS W. SLATER, a citizen of the United States of America, and a resident of Lake Mahopac, county of Putnam, and State of New York, and JAMES T. HOGAN, a citizen of the United States of America, and a resident of Jersey City, county of Hudson, and State of New Jersey, have invented certain new and useful Improvements in Stop-Motions for Sewing-Machines, of which the following is a specification, reference being had to the accompanying drawings, forming a part thereof.

Our invention relates to improvements in stop motions for sewing machines and particularly to stop motions for machines adapted to sew a group of stitches, such as in the formation of button-holes.

The main objects of our invention are to simplify, improve, and strengthen mechanism of this description, such as will bring the driving mechanism quickly to a standstill while absorbing the momentum in such a way as to lessen as much as possible the shock on the parts and to positively bring such driving mechanism to a stop at a predetermined position with respect to the rotation of the drive shaft.

To this end we have devised a mechanism in which a swinging frame is provided with two spring-pressed plungers, one to act as a momentum absorber and in addition to prevent re-coil, and the other to act as a positive limiting stop. The drive shaft is provided with a cam for coöperating with the first said plunger, said cam having a gradual incline in the direction of rotation of the shaft and an abrupt shoulder in the opposite direction, and with a projection for engaging the other said plunger after the said cam and the first said plunger have coöperated.

In order that our invention may be fully understood, we will now proceed to describe in detail an embodiment thereof with reference to the accompanying drawings illustrating the same, and will then point out the novel features in claims.

In the drawings: Figure 1 is a view in side elevation of such parts of a sewing machine as is necessary to illustrate our invention, showing particularly a stop motion embodying the invention. Fig. 2 is an end view thereof. Fig. 3 is a view in horizontal

section through the rear portion of the sewing machine showing the stop motion in top view. Fig. 4 is a view in side elevation of the rear portion of the machine showing the stop motion in a different position to that in which it is shown in Fig. 1. Fig. 5 is a detail transverse sectional view upon the line 5 of Fig. 4 showing particularly the cam and projection carried by the drive shaft. Fig. 6 is a detail view of a portion of the tripping device employed, the same being shown in horizontal line 6-6 of Fig. 4.

The machine herein illustrated comprises the usual bed 10 and overhanging arm 11. The drive shaft 12 is journaled in the said overhanging arm 11, said drive shaft being provided with the usual fast and loose pulleys 13 and 14 respectively. A swinging frame 15 is pivotally mounted at 16 beneath the said drive shaft 12, the axis of the said pivot 16 being transverse with respect to the axis of rotation of the shaft 12, whereby the said frame will swing in a path longitudinally in line with the axis of the shaft 12, as will be well understood. A spring-pressed plunger 17 is mounted to move longitudinally in said swinging frame toward and away from the shaft 12, said plunger being spring-pressed toward the said shaft by means of a spring 18. Tension upon the spring 18 may be regulated by means of a set screw 19. The drive shaft 12 is provided with a cam 20 which is mounted fast thereon, said cam having a gradual incline 21 in the direction of rotation of the said shaft, and a substantially abrupt shoulder 22 in the other direction. The cam 20 and plunger 17 are arranged to be in line with each other and to coöperate when the swinging frame has moved to the position in which it is shown in Fig. 1, but when the said frame is moved into the position in which it is shown in Fig. 4 the said cam and plunger are arranged to be out of line with each other, as will be understood by reference to the drawings. The swinging frame 15 carries another spring-pressed plunger 23, said plunger, in the present instance, being shown as mounted to move longitudinally in a direction transverse with respect to the direction of movement of the first said plunger 17. The plunger 23 is pressed in one direction by means of a spring 24, a screw-threaded end 25 being provided for adjusting the top.

2
sion of the spring. This plunger 23 is provided with a shouldered portion 25 which is arranged to be in the path of movement of a projection 26, carried by a shaft 12, when the swinging frame has been moved to the position in which the first said plunger 17 is in line with the cam 20, as is shown in Fig. 1. The plunger 23 is spring-pressed in a direction opposite to the direction of movement 5 of the projection 26, but will yield by reason of the spring 23 within certain limits, in the direction of movements of said projection.

The operation of these parts is as follows: When the swinging frame is moved to the position in which it is shown in Fig. 1 the cam 15 20 will engage the plunger 17, gradually depressing the same, whereby the momentum of the shaft 12 and parts carried thereby will be gradually absorbed. Finally the said 20 plunger will pass over the projecting portion 21 of the cam and will drop in behind the shoulder 22. At about this moment the projection 26 will engage the shouldered portion 25 of the plunger 23 to positively prevent the 25 shaft from moving any further, except within the slight limits allowed by the yielding of the spring 24. Should the spring 24 yield at all it will thereafter immediately return the plunger 23 to its normal position, and the 30 shouldered portion 22 of the cam 20 will then act as a means to prevent recoil of the parts, the shaft being substantially held in a positive predetermined position by the two said 30 plungers, one acting to prevent movement in 35 one direction and the other to prevent movement in the opposite direction. Such a construction and arrangement of parts not only tends to bring the driving mechanism to rest quietly and without shock to the parts, but 40 as will be readily realized, brings the parts always to rest at a particular predetermined point. The swinging frame is normally held in position in which it is held in Fig. 4, where- 45 in the two said plungers will be out of the path of movement of the cam 20 and projection 26, and tripping mechanism is provided for moving the frame 15 to the position in which it is shown in Fig. 1 when it is desired 50 to stop the machine. The holding means 55 and tripping mechanism comprises a spring 27 which surrounds, and exerts a constant upward pressure upon, a stud 28, said stud being pivotally connected at 29 to an arm 30 secured to the said swinging frame 15. The 55 stud 28 is provided with a collar 31 which is normally engaged by a tripping lever 32 piv- 60 otted at 33 to the bed of the machine. When the device is to be operated the tripping lever is swung upon its pivot to clear the collar 31. 65 The spring 27 will then operate to throw the swinging frame into its operative position (as shown in Fig. 1), and the said frame will remain in such position until it is re-set by being moved back against the resistance of 65 the spring 27 to the position in which it is

shown in Fig. 4, such re-setting being accomplished manually or otherwise, as may be desired.

The swinging frame is provided with a belt 70 shipper 34 whereby at the moment it is dropped it will throw the driving belt from the fast pulley 13 to the loose pulley 14, and similarly, when the frame is re-set, will carry the belt back again from the loose pulley 14 to the fast pulley 13. 75

What we claim is:

1. In a sewing machine, the combination 80 with a swinging frame and two spring 85 pressed plungers mounted therein and carried thereby, one of said plungers constitut- 90 ing a momentum absorber and re-coil pre- 95 venter, and the other, a positive stop, but one which will yield within certain limits, of a drive shaft, a cam mounted thereon for engagement with the first said plunger; a pro- 100 jection carried by said shaft for engagement with the second said plunger, means for moving the swinging frame to bring the said 105 plungers into and out of line with the said cam and projection, and means carried by the said frame for disconnecting said shaft from its driving mechanism.

2. In a sewing machine, the combination 110 with a drive shaft and a cam mounted thereon, of a swinging frame adapted to move in a path longitudinal with respect to the axis of 115 said shaft, a spring plunger carried by said frame, said plunger arranged to move longitudinally in said frame in a direction toward and away from said shaft, a second spring 100 plunger carried by said frame and arranged to move longitudinally therein in a path transverse with respect to the first said plunger, a projection carried by said shaft ar- 105 ranged at certain times to engage the second 110 said plunger, means for normally holding said frame in a position whereby the first 115 said plunger will be clear of the cam and the second said plunger will be clear of the said projection, and means for tripping the said 120 frame to bring the first said plunger in line with the said cam and the second said plunger in line with the said stop.

3. In a sewing machine, the combination 125 with a drive shaft and a cam mounted thereon, of a swinging frame pivoted to move in a path parallel with the axis of rotation of said shaft, a spring-pressed plunger carried by the 130 said frame, said plunger adapted to be moved into line with said cam when the frame is swung in one direction, said cam and plunger arranged to co-operate at such times for the purpose of absorbing the momentum of the shaft but not for bringing the shaft to rest, a stop projection carried by said shaft, and a second spring plunger carried by said frame arranged to yield in a direction trans- 135 verse to the direction of movement of the first said plunger, said stop and second plunger co-operating to form a yielding stop to

prevent other than slight further movement of the shaft after said cam and first named plunger have coöperated, and means for moving the said frame whereby to bring the said 5 first named plunger into and out of line with the said cam.

4. In a sewing machine, the combination with a drive shaft and a cam mounted thereon, said cam having a gradual incline in the 10 direction of movement of the shaft, and an abrupt shoulder in the opposite direction, of a swinging frame pivotally mounted adjacent to said drive shaft, the pivotal axis thereof being transverse with respect to the axis of 15 said drive shaft, a spring-pressed plunger carried by said frame arranged, when the frame is moved in one direction, to coöperate with the said cam and to be moved longitudinally whereby to absorb the momentum of

said shaft, a projection carried by said shaft, 20 a second spring plunger carried by said frame and arranged to coöperate with said projection when the frame is moved to a position wherein the first said plunger is in line with the cam, said shaft being prevented from 25 further movement in a forward direction by the engagement of said stop with said projection and from return movement by the engagement of said first named plunger with the shouldered portion of said cam, and 30 means for swinging the frame upon its pivots to carry the plungers into and out of line with the said cam and projection.
